PUMPING APPARATUS

Harrison S. Coe, Palo Alto, Calif.

Application March 8, 1946, Serial No. 652,978

9 Claims. (Cl. 103—44)

1

This invention relates to pumping apparatus of the type in which a diaphragm, actuated by recurrent impulses of suction and pressure, imparted by a plunger acting against an impelling liquid in an impelling liquid chamber, causes a pumping compartment which is separated by the diaphragm from said impelling liquid chamber, to alternately expand and contract in the process of pumping, generally as shown in my co-pending application Serial No. 608,850 filed August 4, 1945, for a Pumping apparatus, now abandoned.

One object of the present invention is to provide novel means whereby the diaphragm in a pump of the type described is protected against rupture, on starting the pump, after the same has become displaced from its normal position in relation to the position of the plunger due to leakage of liquid during a period of idleness.

Another object of my invention is to provide novel means whereby, if the diaphragm becomes so displaced, while the pump is idle, it will, when the pump is started, be drawn into its normal locus of oscillation.

Another object of my invention is to provide novel means adapted to be employed in adjusting the capacity at which the pump is operated.

Generally speaking, my invention consists of means adapted to prevent excessive introduction of liquid and to cause the admission of air into the impelling liquid chambers of the pump when the pumping compartment contracts during periods of idleness, and means adapted to permit the expulsion of said air during the starting of the pump and, thereafter, of preventing or controlling the admission of such air into said compartment during periods when the pump is in operation.

Other objects and advantages will appear from the following specification and drawings in which:

Figure 1 is a vertical sectional view of a diaphragm pump of the type described illustrating the form and position of a mechanism adapted to establish the zone of oscillation of the diaphragm and of elements adapted to function in my invention.

Figure 2 is a detailed vertical side elevation partly in section of means mounted on the pump shown in Figure 1 and adapted to function with the present invention and in stabilizing the zone of oscillation of the diaphragm.

Figure 3 is a side elevation of the assembly shown in Figure 2.

As shown in Figure 1 a cylindrical member 10 and peripherally extending plate members 11 and 12 enclose a chamber 13, of which members 11

2

and 12 form, respectively, the upper and lower walls, and in which is incorporated a pumping or impelled liquid compartment 14, which is separated from the impelling liquid chamber 13 by a tubular diaphragm 15.

Diaphragm 15 may be of rubber or other pliable material and preferably has a relatively thick lower section, a thinner central section of greater diameter when open than has either end section and a smaller bore at its upper or outlet end.

Lower wall 12 of chamber 13 is provided with an inwardly flaring orifice 20 which is adapted to receive a tubular gasket 21 and the lower portion 22 of tubular cage-like member 23. Lower wall 15 portion 22 is tapered in such a manner that it cooperates with the wall of orifice 20 to provide a wedging effect whereby a leak proof seal there between is obtained. The upper end 24 of member 23 is provided with a peripheral flange 25 which is adapted to cooperate with wall 11 of chamber 13 and to be secured in leak proof contact therewith by screws 26 and gasket 27. The upper portion 24 and the lower portion 22 of member 23 are rigidly connected by spacing members 28 which are of a length adapted to cause the wedging effect of portion 22 in orifice 20 as required to compress gasket 21.

I have also provided an open tubular member 30 flanged at its upper end and provided with ori-fices 31 opposite the open areas 29 between spacing members 28 in member 23 with its flange 32 resting on the upper surface of annular flange 25.

Diaphragm 15 is adapted for mounting at its lower and upper ends and is held in impervious contact with the outer surfaces 34 and 35 of portions 22 and 24 respectively of cage member 23. In mounted position, diaphragm 15 encloses pumping compartment 14 and tubular member 30 extends downwardly, co-axially, within it from the outlet end of said compartment.

Plate member 11 in conjunction with casing 36, which is secured in sealed contact therewith by means of bolts 37 and gasket 38, constitutes a valve case 39, in which is mounted an outlet valve assembly 40 which is adapted to conduct fluid being expelled from compartment 14 to a discharge pipe 41. Valve 40 is adapted to prevent a counter-flow of fluid from pipe 41 to compartment 14.

The upper wall of case 39 is provided with a circular aperture 42 which is co-axially aligned with tubular member 30 and cylindrical member 10. A cover plate 43 is adapted to close aperture 42 and a liquid proof contact between casing 39 and plate 43 is secured by means of a gasket 44 and bolt 45. The lower inner wall of cover 43 is

formed to fill excess space which would normally occur between cover plate 43 and member 11 and is provided with an extending lip 46 which is adapted to engage flange 32 of tubular member 30 and hold the same in the position shown in Figure 1.

Plate member 12, in combination with a casing 47 which is secured in sealed contact therewith by means of bolts 48 and gasket 49, constitutes a valve case 50, in which is mounted an inlet valve assembly 51 which is adapted to conduct fluid being drawn into pumping compartment 14 through valve assembly 51 which is also adapted to prevent counter-flow of liquid through it from said pumping compartment.

Chamber 13 is provided with outlet 53 which communicates with a cylinder 54 within which a reciprocating piston (not shown) is positioned and adapted to reciprocate therein as indicated by the arrow.

Perforated plate members 55 are mounted in cylinder 10 to support diaphragm 15 against over expansion if valve 40 leaks while the pump is idle.

As will hereinafter more fully be explained, the space 13 within casing 10 and outside of the diaphragm 15 is termed an impelling liquid chamber and the same is filled with liquid hereinafter called "impelling liquid." Upon reciprocation of the piston within cylinder 54 impelling liquid is alternately drawn out of and forced into the space 13 thereby creating alternate suction and pressure pulsations therein, which in turn cause pumping compartment 14 to alternately expand and draw in fluid being pumped through valve case 50 and valve 51 and contract and expel said fluid through valve case 39 and valve 40.

As has more fully been pointed out in my United States Letters Patent No. 2,405,734, granted August 13, 1946, for a Pumping apparatus, on such strokes of the piston within cylinder 54 a small amount of air may be drawn into the impelling liquid compartment and ultimately this air seeks the highest point therein. Furthermore there is a certain leakage of fluid at the piston which actuates the impelling liquid. The above referred to copending application provides means to prevent air from accumulating in the impelling liquid compartment and to replace liquid escaping therefrom.

During a period of idleness of the pump, leakage of fluid from pumping compartment 14 through inlet valve 51 may cause the inward displacement of diaphragm 15 from its normal position. If the piston in cylinder 54 is in position to start on a pressure stroke after such leakage occurs, diaphragm 15 may be completely collapsed and, unless relief means are provided, it may be ruptured by being forced into the outlet conduit leading from compartment 14 on starting the pump. I have provided means whereby, if the diaphragm becomes so displaced, while the pump is idle, it will, when the pump is started, be relieved of excessive strain and be drawn into its normal locus of oscillation, said means consisting of means adapted to prevent excessive entrance of liquid and to cause the admission of air into the impelling liquid compartment of the pump when the pumping compartment contracts, during periods of idleness, and means adapted to permit the expulsion of said air during the interval of starting the pump, and, thereafter, of preventing or controlling the admission of such air into the impelling liquid compartment during periods when the pump is in operation.

As shown more particularly in Figures 2 and 3, the aforementioned means are incorporated in the air and liquid inlet and outlet system shown generally at 56 and in the liquid inlet apparatus 5 shown generally at 57.

Air inlet and outlet system 56 may briefly be described as follows:

Tubular conduit 60 communicates with passageway 61 in cylinder 10 and with the impelling liquid chamber 13. A threaded casing 62 communicates with and is supported at its upper end by conduit 60 and is adapted to permit the passage of fluid therethrough past an adjustable threaded member 63, mounted therein, to a conduit 65. Conduit 65 communicates with an enclosed chamber 66 within which there is mounted a cup 67 in which the lower end of conduit 65 is mounted. Chamber 66 is provided with orifices 68 by which the same is vented to the atmosphere. Chamber 66 is also provided with outlet orifices 69 and 70, the former of which communicates with conduit 71 which leads through pet cock 72 from the bottom of chamber 66 to compartment 73 in tank 74. Outlet 70 communicates with conduit 75 which leads from a higher level in chamber 66 than does conduit 71 to compartment 76 of tank 74.

Cup 67 is adapted to receive liquid at a point near its bottom from the outlet end of conduit 65 and to permit the overflow of said liquid into the surrounding space in chamber 66 at a higher level.

As shown more particularly in Figures 2 and 3 the liquid inlet system 57 comprises a cylindrical member 80 which is provided with flanges 81 and 82 and is adapted to fit within orifice 83 in the wall of cylinder 10. It is secured to the wall of cylinder 10 by means of bolts 84. A plate 85 closes the outer end of cylindrical member 80 and is held in impervious relationship thereto as by means of bolts 86 and gasket 87.

A tubular member 88 is mounted within cylindrical member 80, co-axially therewith, and is provided with a flange 89 which, in turn, is provided with threads 90 which are adapted to cooperate with corresponding threads 91 in cylindrical member 80. A threaded plate 92 closes the outer end of cylindrical member 88 and is provided with an orifice 93 adapted to receive push rod 94. Push rod 94 is provided at one end with a facing member 95 which is adapted to contact the diaphragm 15, and a valve pallet 96 which is adapted to engage the inner wall of wall 92 as shown in Figure 2 and prevent the flow of liquid from within cylindrical member 88 into the space within member 10. Orifice 93 is adapted to guide push rod 94 as well as permit the flow of liquid therethrough. Plunger 98 is secured to the inner end of push rod 94 and engages a spring 99 which is adapted to urge valve 96 toward the closed position shown in Figure 2. Tubular member 88 is closed at its inner end by a plate 100 which is provided with an orifice 101 to which is secured a pinched rubber valve member 102 which is adapted to permit the flow of liquid from within tubular member 88, and to prevent a counterflow of liquid through it into the same. Another and smaller orifice 103 is provided to permit the inflow and outflow of liquid from the space within tubular member 88 behind plunger 98.

Cylindrical member 88 is provided with another orifice 104 which permits the inflow and outflow of liquid from within that space within tubular member 88 in front of plunger 98.

Tank 74 has previously been mentioned herein. It comprises an outer supply compartment 73 and a smaller inner compartment 76 and is secured to the pump in any suitable manner and generally positioned below both the air and liquid inlet and outlet system 56 and the liquid inlet system 57.

Tubular conduit 110 is fixed to the upper wall of tubular member 60 and is connected to a T-fitting 111, one outlet of which is joined to conduit 112 which terminates in a ball check valve device 113 near the bottom of compartment 76. Ball check valve 113 is adapted to permit the flow of liquid into the space within tubular member 80 through conduit 112 but to prevent the outflow of liquid therefrom through said conduit. The other outlet of T-fitting 111 communicates with conduit 115 which leads through pet cock 116 into compartment 76. A restricted orifice device 117 is placed within conduit 115 below pet cock 116 to cause resistance to the flow of fluid therethrough.

Compartment 76 is provided with an orifice 120 on the wall thereof to provide communication between compartments 76 and 73 of tank 74. A float 121 is provided in compartment 76 and is maintained in an aligned position over orifice 120 by a bracket 122 as shown. A valve member 123 is secured to the lower side of float 121 and is adapted to abut against the up-turned flange 124 around orifice 120 to provide a seal against the flow of liquid from compartment 73 into compartment 76 when the liquid level within compartment 76 falls to such a level that valve pallet 123 and up-turned flange 124 are in contact.

The operation of the device may briefly be described as follows:

This may best be done by describing the actions in the pump both under normal operating conditions and when it is stopped and later started after a period of idleness during which leakage has occurred.

Let it be assumed that the diaphragm 15 is in the position shown in Figure 1 and that all of the spaces in the pump are filled with appropriate liquids. Let it further be assumed that cup 67 and tank 74 including compartment 76 are filled with liquid adapted to be employed as impelling liquid and that the pump is at the end of a pressure stroke.

On the following suction stroke the withdrawal of liquid upon the reciprocation of the piston in cylinder 54 causes the withdrawal of liquid from the impelling liquid compartment 13 and creates a condition of suction in the pumping compartment 14, causing liquid to enter through valve case 50 and valve 51 and causing diaphragm 15 to assume the broken line position 15a shown in Figure 1. When the diaphragm is near the end of the suction stroke it engages disc 95 and causes rod 94 to move inward in tube 88, thereby opening valve 96 and permitting communication between the impelling liquid compartment and the interior of tubular member 80. Spring 99 is compressed and plunger 98 forces evacuation of a quantity of the liquid behind it through orifice 103 and valve 102.

Normally, since the diaphragm 15 engages disc 95 near the end of the suction stroke, when the velocity of the plunger of the pump is being decelerated at a high rate, the liquid in compartment 13 is under pressure when the valve 96 is open and no liquid is drawn into the impelling liquid compartment 13 during the balance of the

suction stroke. However, during the following pressure stroke, the diaphragm 15 moves away from the disc 95 but valve 96 is retarded in its closing due to the time required for the replacement of liquid previously expelled from that area behind plunger 98 through orifices 103 and 102. During this period the fluid being pumped is expelled from the pumping compartment 14 through valve 40 and, concurrently, a small volume of liquid is expelled from impelling liquid compartment 13 through orifice 61, conduit 60, and member 62. This liquid fills and over-flows the inner cup 67. The liquid overflowing inner cup 67 is divided, and one portion of essentially constant volume passes through conduit 71 into compartment 73. The balance passes through conduit 75 into compartment 76. On starting the following suction stroke valve 96 is not yet closed and liquid is drawn from the interior of cylinder 80 through orifice 104 and valve 96, into chamber 13 and a like volume of impelling liquid is drawn into cylinder 80 through valve 113 and conduit 112. A small quantity of liquid also enters the impelling liquid compartment 13 during the suction stroke from cup 67 through conduit 65, casing 62, conduit 60 and orifice 61.

In such normal operation the outward limits of movement of diaphragm 15 is automatically established and remains constant at a location at which plunger 98 displaces a volume of liquid in the compartment behind the plunger 98, the return of which, through orifice 103, under the influence of spring 99 acting against the plunger 98, retards the closure of valve 96 just long enough for the volume of liquid being drawn from the compartment 76 into the pump to compensate for all liquid being lost to chamber 13 and not returned through the orifice 61.

If, however, the pump is stopped and it happens that liquid is leaking out of the pumping compartment 14, as for example through inlet valve 51, fluid in a compensating volume must enter the impelling liquid compartment 13 either through orifice 61, valve 96, or cylinder 53.

Since the level of liquid within the cup 67 is higher than the level of liquid in tank 74, the compensating fluid enters the impelling liquid compartment 13, preferentially through orifice 61 at a rate up to that at which resistance to flow in the resistance element 62 balances the pressure required to open valve 113 plus the difference between the hydrostatic pressure in the impelling liquid compartment 13 at the level of the liquid in cup 67 and in tank 76. Such compensating addition of fluid, if it is a liquid, in the impelling liquid compartment 13, creates a condition in the pump in which the pumping compartment 14 is in a state of partial or total contraction whereas the plunger 54 of the pump is in a position to force a further and abnormal contraction of said compartment when the pump is started, and thereby to force the diaphragm 15 into the member 30 and rupture it.

If, however, the compensating fluid being drawn into the impelling liquid compartment is air, the volume which may be expelled through orifice 61 and member 62 under a given pressure is very much greater than if it is liquid, and since the starting stroke of the pump is relatively slow it may be expelled without strain upon the diaphragm.

One means which I have provided to cause the introduction of air instead of liquid under the above described condition is illustrated by cup

member 67 in combination with tube 65, in conjunction with vents 68.

In operation this means functions as follows: Cup 67 fills and overflows during the pressure stroke of the pump and is partly evacuated during the suction stroke. When the pump is stopped and slow leakage, as previously described, occurs from the impelled liquid compartment, cup 67 is very quickly emptied and thereafter air is drawn into the impelling liquid compartment through orifices 68, tube 65, member 62, tube 64 and orifice 60. When the pump is started this air is forced out of the impelling liquid compartment through orifice 61 and member 62 under moderate pressure and, it is found, all of the air will have been evacuated from the impelling liquid compartment after a few strokes of the pump and operation will become normal. If, however, the pump is stopped at the end of the suction stroke and a very fast leakage of the liquid from the impelled liquid compartment takes place, liquid is drawn into the impelling liquid compartment 13 by the way of valve 96 before the latter has reached a closed position.

The other means suited to prevent an excessive admission of liquid into the impelling liquid compartment under the above described condition is illustrated in connection with small compartment 76 in supply tank 74 in which the orifice 120 is provided for the entrance of an essentially constant uniform return of impelling liquid to compensate for that leaking past the plunger 54 of the pump, and the constant volume fraction of the liquid being expelled from the impelling liquid compartment 13 through orifice 61 and being diverted, for cooling purposes, to the compartment 74. This is a very small volume generally not exceeding one or two cubic inches for each stroke of the pump and orifice 120 is correspondingly small. During operation the liquid level in compartment 76 is not far below that in compartment 74 and during normal operation float valve 121 remains completely open, but if, on stopping the pump, liquid is drawn through the ball valve 113 in an excessive amount the liquid in chamber 76 falls and valve 123 closes to prevent the further admission of liquid into compartment 76 and air is subsequently drawn into the cylinder 89. When starting the pump the air so admitted into cylinder 89 is ejected by opening the cock 116 or, if constriction 117 is sufficiently narrow, cock 116 may be left open without materially affecting the capacity of the pump.

In the event it becomes desirable to reduce the capacity of the pump, the same may be obtained by varying element 63 to permit an increased outflow of liquid from the impelling liquid compartment 13 and on the succeeding suction stroke to empty cup 67 and thereafter draw air through orifices 68, conduit 65 and orifice 61 into the impelling liquid compartment.

I claim:

1. In a pump having an expansible and contractable pumping compartment, an impelling liquid chamber and a diaphragm separating said compartment from said chamber, said diaphragm being adapted to pulsate in response to suction and pressure pulsations of liquid in said impelling liquid chamber, means adapted to admit air into said chamber under the influence of suction pulsations therein, said means including a hollow member adapted to receive liquid during the operation of the pump and to be evacuated of liquid prior to the admission of air into said chamber.

2. In a pump having an expansible and con-

tractable pumping compartment, an impelling liquid chamber, a diaphragm separating said compartment from said chamber, and means adapted to prevent the admission of air into said chamber when the pump is in operation, and to admit air into said chamber under the influence of suction generated by the contraction of said compartment due to the outward leakage of liquid from said compartment when the pump is idle.

3. In a pump having an expansible and contractable pumping compartment, an impelling liquid chamber and a diaphragm separating said compartment from said chamber, said diaphragm being adapted to pulsate in response to suction and pressure pulsations of liquid therein and to cause successive periods of change in the volume of said pumping compartment, means adapted to prevent the admission of air into said chamber when the pump is in operation and to admit air into said chamber under the influence of suction generated therein by the contraction of said compartment due to the outward leakage of liquid from said compartment when the pump is idle, said means including a hollow container adapted to receive liquid during the operation of the pump and means adapted to function in lowering the level of the liquid in said container under the influence of said suction in said chamber and thereafter to function in admitting air into said chamber under the influence of continued suction therein.

4. In a pump of the character described comprising a plurality of intercommunicating chambers adapted to contain impelling liquid, an expansible and contractable pumping compartment and a diaphragm separating said compartment from said chambers, a conduit adapted to communicate said compartment with a source of fluid to be pumped, a valve adapted to prevent the outward passage of fluid from said compartment into said conduit, means adapted to admit air into at least one of said chambers under the influence of suction generated by the contraction of said compartment due to the outward leakage of liquid of liquid therefrom through said valve while the pump is not in operation.

5. In a pump of the character described comprising a plurality of intercommunicating chambers adapted to contain impelling liquid, an expansible and contractable compartment and a diaphragm separating said compartment from said chambers, a conduit adapted to communicate said compartment with a source of fluid to be pumped, a valve adapted to prevent the outward passage of fluid from said compartment into said conduit, means adapted to admit air into at least one of said chambers during the period of contraction of said compartment due to the outward leakage from said compartment through said valve while the pump is not in operation, and means to admit a predetermined volume of water and an adjustably controlled volume of air into said chamber at each stroke of the pump.

6. In a pump having an expansible and contractable pumping compartment, a conduit adapted to communicate said compartment with a source of fluid to be pumped, an outwardly closing valve adapted to prevent the passage of fluid from said compartment into said conduit, an impelling liquid chamber and a diaphragm separating said compartment from said chamber, means adapted to admit air into said chamber under the influence of suction generated by the contraction of said compartment due to the

outward leakage of fluid from it through said valve, said means including a hollow member adapted to receive liquid during the operation of the pump and to be evacuated of said liquid prior to the admission of air into said chamber.

7. In a pump having an expandable and contractable pumping compartment, a conduit adapted to communicate said compartment with a source of fluid to be pumped, an outwardly closing valve adapted to prevent the passage of fluid from said compartment into said conduit, an impelling liquid chamber and a diaphragm separating said compartment from said chamber, means adapted to admit a controlled volume of liquid and air into said chamber under the influence of suction generated by the contraction of said compartment due to the outward leakage of fluid from it through said valve during a period when the pump is not in operation.

8. In a pump having an expandable and contractable pumping compartment, a conduit adapted to communicate said compartment with a source of fluid to be pumped, an outwardly closing valve adapted to prevent the passage of fluid from said compartment into said conduit, an impelling liquid chamber, a diaphragm separating said compartment from said chamber, and a plunger adapted to create, alternately, pressure and suction in said impelling liquid chamber, means adapted to prevent the admission of air into said chamber under the influence of suction created by the plunger while the pump is in operation, and to admit air into said chamber under the influence of suction in said chamber generated by the contraction of said compartment due to the leakage of fluid from it through said valve during a period when the pump is not in operation.

9. In a pump having an expandable and contractable pumping compartment, a conduit

40

adapted to communicate said compartment with a source of fluid to be pumped, an outwardly closing valve adapted to prevent the passage of fluid from said compartment into said conduit, 5 an impelling liquid chamber, a diaphragm separating said compartment from said chamber, and a plunger adapted to create, alternately, pressure and suction in said impelling liquid chamber, means adapted to prevent the admission of air into said chamber under the influence of suction created by the plunger while the pump is in operation, and to admit air into said chamber under the influence of suction in said chamber generated by the contraction of said compartment due to the leakage of fluid from it through said valve during a period when the pump is not in operation, 10 15 20 25 30 35 40
